UNITED STATES PATENT OFFICE.

JACOB C. LOWREY, OF WILMINGTON, DELAWARE, ASSIGNOR TO HENRY M. LOVE, OF WILMINGTON, DELAWARE.

DESIGN FOR A KNITTED UNDERGARMENT.

SPECIFICATION forming part of Design No. 35,350, dated November 26, 1901.

Application filed October 5, 1901. Serial No. 77,747. Term of patent 14 years.

To all whom it may concern:

Be it known that I, JACOB C. LOWREY, a citizen of the United States, and a resident of Wilmington, Delaware, have invented and produced a new and original Design for a Knitted Undergarment, of which the following is a specification.

My design for a knitted undergarment is fully shown in the accompanying drawing, which illustrates a view in elevation.

The essential feature of my design consists of a pair of drawers, shaped as shown, wherein the numerals 1 1 represent the legs of the drawers, which have flaring lower ends 2, conventionally shown as knitted with a stitch different from that in the upper portions of the legs, these flaring portions of the legs be-

ing finished with flaring lace trimming 3, thus constituting a double flare on each leg, one composed of knitted stitch and the other of lace trimming.

Having thus described my invention, I claim and desire to secure by Letters Patent—

The design for a knitted undergarment, substantially as described and as shown in the accompanying drawing.

In testimony whereof I have signed my name to this specification in the presence of two subscribing witnesses.

JACOB C. LOWREY.
